UNITED STATES PATENT OFFICE.

JAMES S. PATTEN, OF BALTIMORE, MARYLAND.

DESIGN FOR A SOUNDING TOY.

SPECIFICATION forming part of Design No. 34,195, dated March 5, 1901.

Application filed February 5, 1901. Serial No. 46,146. Term of patent 14 years.

To all whom it may concern:

Be it known that I, JAMES S. PATTEN, a citizen of the United States, residing at Baltimore, in the State of Maryland, have invented and produced a new and original Design for Sounding Toys, of which the following is a specification, reference being had to the accompanying drawings, forming part thereof, in which—

10 Figures 1 and 2 are side elevations taken, respectively, in the directions indicated by the arrows No. 1 and No. 2 in Fig. 4. Fig. 3 is a longitudinal section on about the line 3 3 of Fig. 4, and Fig. 4 is a bottom end view 15 of the toy.

The toy comprises the body A, which is shown in Fig. 3 with a socket A' to receive the end of a cane or other staff, and at the lower end of said body are provided the depending legs B, whose outsides are in alignment with the outer side of the body A and which taper toward their lower ends, being

separated by intervening spaces C, which flare toward their lower ends, as shown in Fig. 1, and also flare laterally or outward, as shown 25 in Fig. 4, and the lower ends of the legs B are rounded on their outer sides and present square faces at their lower ends, which lower ends are spaced apart a proper distance and are curved on their inner faces, as shown in 30 Fig. 4, thus fitting them to receive between them an explosive cap.

Having thus described my invention, what I claim as new, and desire to secure by Letters Patent, is—

The design for a sounding toy, as herein shown and described.

In testimony whereof I have signed my name to this specification in the presence of two subscribing witnesses.

JAMES S. PATTEN.
